Patented Oct. 7, 1913

UNITED STATES PATENT OFFICE.

GEORGE F. STEEDMAN, OF ST. LOUIS, MISSOURI.

PRESSURE-CONTROLLING DEVICE.

1,075,170.

Specification of Letters Patent.

Patented Oct. 7, 1913.

Application filed November 22, 1912. Serial No. 732,862.

To all whom it may concern:

Be it known that I, GEORGE F. STEEDMAN, a citizen of the United States, residing at St. Louis, Missouri, have invented a certain new and useful Improvement in Pressure-Controlling Devices, of which the following is a full, clear, and exact description, such as will enable others skilled in the art to which it appertains to make and use the same.

This invention relates to pressure controlling devices of the type which comprise means for actuating a member that governs the supply of an expansible or pressure medium to a storage chamber or reservoir so as to automatically cut down the supply when the pressure in the storage chamber reaches or exceeds a certain degree and also cause the supply to be resumed when the pressure in the storage chamber drops below a certain degree.

The principal object of my invention is to provide a simple and rugged device of the type referred to that comprises no delicate parts and is positive in action under commercial conditions as found when these devices are used or maintained by unskilled persons.

Another object of my invention is to provide a pressure-controlling device of the type referred to which is so constructed that a comparatively slight or immaterial drop in pressure after the controlled member has been rendered inoperative, will not affect the device or cause the movable parts of same to act, thereby preventing the device from operating too frequently and thus wearing out quickly.

Another object is to provide a pressure-controlling device that comprises a valve mechanism which is so designed that a greater area of the valve is presented to the action of the expansible medium that unseats the valve after the valve has been opened, than is presented to the action of said expansible medium when the valve is seated, the valve moving to its open position as soon as the pressure of the expansible medium that acts on same overcomes the force of the means that holds the valve seated, and remaining open, due to the additional exposed area of same, until the pressure of the expansible medium drops materially or to such a degree that the pressure per square inch is slightly less than the reduced area of the valve that is ex-

posed when the valve is seated and less than the force of the valve-closing means. For example, if the entire area of the valve is one square inch but only $\frac{1}{16}$ of the valve is exposed to the expansible medium when the valve is seated, and a spring whose force is equal to 90 lbs. pressure per square inch is employed to hold the valve seated, the valve will not open until the pressure of the expansible medium exceeds 100 lbs. per square inch, due to the fact that the exposed area of the valve is only $\frac{1}{16}$ square inches but after the valve opens it will remain open until the pressure of the expansible medium drops below 90 lbs. per square inch. And still another object is to provide a pressure-controlling device of the type referred to in which the movable part that actuates the member to be governed consists of a packingless piston which is so constructed that the expansible medium that moves same cannot leak around the piston, thereby enabling the device to be used successfully for controlling the pressure of a storage chamber that contains steam or various other mediums that have a deleterious effect on leather and similar materials such as are generally used for packing the pistons of pressure-controlling devices.

Other objects and desirable features of my invention will be hereinafter pointed out.

I have herein shown my improved pressure-controlling device used for governing the suction valves of an air compressor that is connected with a storage chamber or reservoir, so as to hold said valves from their seats automatically and thus cause the compressor to become inoperative when the pressure in the storage chamber or reservoir reaches or exceeds a certain degree and allow said valves to resume normal function so as to render the compressor operative when the pressure in the storage chamber drops below a certain degree, but I do not wish it to be understood that my invention is limited to this specific use for it can be used for automatically governing any kind of a mechanism that controls the supply of an expansible or pressure medium to a storage chamber or reservoir.

Figure 1 of the drawings is a vertical sectional view of a pressure-controlling device constructed in accordance with my invention, and shows a portion of an air compressor whose suction valves are automatically

governed by said device; and Fig. 2 is a horizontal sectional view taken on the line 2-2 of Fig. 1.

Referring to the drawings which illustrate the preferred form of my invention, A designates one of the suction valves of a compressor B which is connected with a storage chamber or reservoir, not shown, and C designates a lever that moves said valve so as to hold it from its seat, against the force of the spring D which normally allows the valve to be seated.

My improved pressure-controlling device consists of a cylinder 1 provided with a piston 2 that acts upon the valve-controlling lever C, a pressure chamber 3 that is connected with the storage chamber or reservoir, not shown, by means of a supply pipe 4, and a diaphragm 5 arranged over said pressure chamber which acts as a valve for controlling the flow of the expansible medium through the port or duct 6 that establishes communication between the pressure chamber 3 and the cylinder 1 in which the piston 2 operates. The diaphragm 5 acts as diaphragm and valve, and a spring-pressed plunger 7 is arranged above the same, as shown in Fig. 1, so as to hold the valve seated, the supply pipe 4 which establishes communication between the pressure chamber and the storage reservoir entering the lower portion of the pressure chamber so that the expansible medium will exert upward pressure on the under side of the valve or diaphragm 5 and thus tend to raise it from its seat. In order that the plunger 2 will not operate incessantly or too frequently when the pressure in the storage chamber or reservoir varies immaterially or slightly, I have constructed the device in such a manner that a greater area of the diaphragm valve 5 is exposed to the action of the expansible medium in the pressure chamber after said valve opens than is exposed to said expansible medium when said valve is closed, thereby causing the valve 5 to remain open after it has been unseated until the pressure in the storage chamber has dropped materially or proportionally to the rise in pressure which caused the valve to open. In the preferred form of my invention as herein shown this is accomplished by using a flat, disk-shaped diaphragm valve 5 and forming a raised valve-seat 5^a at the center of the pressure chamber 3 that practically covers the center portion of the valve 5 when it is seated and thus prevents the entire area of the valve from being exposed to the action of the expansible medium that tends to unseat the valve. The valve-seat 5^a preferably consists of an annular rib on the bottom of the pressure chamber 3 that surrounds the port 6, and the upper edge of said rib is made comparatively sharp so that the valve 5 will be sure to fit tightly against

its seat. In this way I obtain two different valve areas, the lesser area being exposed to the action of the expansible medium when the valve is seated and the greater area being exposed when the valve is unseated. If the entire area of the under side of the diaphragm valve 5 is one square inch, the area of the ring-shaped valve seat 5^a is $\frac{1}{16}$ of a square inch, and the spring 7^a that acts on the plunger 7 which holds the valve seated has a force corresponding to 90 lbs. pressure per square inch, the valve 5 will remain seated until the pressure in the storage reservoir and supply pipe 4 exceeds 100 lbs. pressure per square inch, this, of course, being due to the fact that the area of the under side of the valve which is exposed to the pressure in the supply pipe 4 is only $\frac{1}{16}$ of a square inch. As soon as the pressure exceeds 100 lbs. and the valve 5 opens, the valve area is increased 10% due, of course, to the uncovering of the center portion of the valve and consequently the entire under side of the valve will be exposed to the pressure in the pressure chamber 3. As soon as the valve 5 opens, the expansible medium flows through the duct or port 6 and imparts movement to the piston 2, thereby causing the lever C to open the suction valves D and thus render the compressor inoperative. After the valve 5 has been opened, it remains open until the pressure in the storage reservoir and supply pipe 4 drops below 90 lbs. pressure per square inch; or, in other words, until the force of the spring 7^a overcomes the force of the expansible medium that unseated the valve, the piston 2 which acts upon the controlled members C remaining at rest until the valve 5 closes the port 6 that establishes communication between the cylinder 1 and the pressure supply line 4. After the valve 5 closes, the expansible medium in the upper portion of the cylinder 1 escapes through a branch port 6^a in which a leak screw 8 is arranged, thereby permitting the piston 2 to move upwardly and thus causing the compressor to become operative. A by-pass 9 that is controlled by a valve 10, leads from the pressure chamber 3 to the cylinder 1 so as to enable pressure to be applied to the piston 2 and thus cause the suction valves D of the compressor to open when it is desired to do so independently of the automatic action of the device. The range of pressure between the pressures at which the diaphragm valve opens and closes is proportional to the difference in areas of the diaphragm valve exposed to pressure when said valve is away from its annular seat and when against said seat, so that for a considerable range in pressure I provide an annular valve seat of comparatively large diameter, and for a smaller range in pressure I provide a smaller annular valve seat. It is obvious that this desirable object can

be secured by using inserted valve seats of various sizes rather than a solid valve seat as herein shown.

I am aware that separate conical valves attached to and operated by a diaphragm over a pressure chamber have been used for years, and that said separate valves give a differential pressure action when they are well made and in exact working condition. I have found, however, that said separate valves are delicate, and liable to get out of working order and are not as simple or dependable as the rugged and simple device herein shown which omits the separate valve and uses the diaphragm directly as a valve. My simple device also permits of employing a smaller valve-seat and a less range in pressure than would be commercially practicable with the separate valve. My improved device costs less than the older devices and is much more positive and dependable.

From the foregoing it will be seen that a pressure-controlling device of the construction above-described effectively and positively controls the pressure in a storage chamber or reservoir in such a manner that the pressure cannot exceed a certain degree but it can drop materially below the normal pressure after the pressure-producing means has been rendered inoperative, before said pressure-producing means is again rendered operative; the chief advantage of such a device being that it does not operate incessantly or too frequently and consequently will not wear out quickly.

In addition to the desirable feature above-mentioned my device is adapted for use with practically any kind of an expansible medium owing to the fact that the piston 2 which actuates the controlled member is a packingless piston and is so designed that the expansible medium which actuates same cannot leak around the piston. As shown in Fig. 1, the cylinder 1 in which the piston 2 is arranged is provided with two portions of different diameters, and the piston 2 is also provided with two portions that are of different diameters. The upper portion *a* of the piston 2 is of greater diameter than the lower portion *b*, and a beveled surface *c* is formed at the junction of the two portions of the piston. A correspondingly-shaped beveled seat *c'* is also formed at the junction of the upper and lower portions of the cylinder 1. Consequently, when pressure is admitted to the upper end of the cylinder 1 the piston 2 will be forced downwardly until the beveled seat *c* thereon rests upon the beveled surface *c'* on the inside of the cylinder 1, said coöperating beveled surfaces forming a tight joint between the piston and the cylinder, similar to a commercial check valve seat, which prevents the expansible medium from leaking around the

piston. The fact that the piston 2 is not packed with leather or any other material such as is generally used for packing the pistons of pressure-controlling devices makes it possible to successfully use my improved device in connection with steam and other expansible mediums that have a deleterious effect on piston packing materials.

In order to prevent scale and other particles of foreign matter which pass through the supply pipe 4 from lodging between the valve 5 and the seat, I prefer to arrange a layer of filtering material 12 in the pressure chamber 3 in such a manner that the expansible medium which enters said chamber will pass through said material and thus be filtered.

Having thus described my invention, what I claim as new and desire to secure by Letters Patent is:

1. In a pressure-controlling device, the combination of a packingless piston that is adapted to actuate a member which it is desired to control, a supply port leading to the cylinder in which said piston moves, a diaphragm valve for controlling said port and which is adapted to be unseated automatically when the pressure that is being regulated reaches and exceeds a certain degree, thereby causing the pressure to enter said cylinder and act on the piston therein, and means whereby a greater area of said valve is presented to the action of the pressure medium after the valve has been unseated than is presented to the action of said pressure medium when the valve is seated, thereby causing the valve to remain open and thus cause the pressure to act on said piston until the pressure has dropped to a greater degree proportionally than the rise in pressure which caused the valve to open.

2. A pressure-controlling device provided with a packingless piston that is reciprocatingly mounted inside of a cylinder, a controlled member which said piston acts upon, said piston having a beveled surface, and a coöperating beveled surface on the interior of the cylinder so as to form a tight joint between the piston and the cylinder when the piston is at the end of its pressure stroke.

3. A pressure-controlling device provided with a packingless piston that acts on a member which it is desired to control, the head of the piston on which the operating medium acts being of greater diameter than the body portion of the piston, a cylinder having two portions of different diameters in which the head and body portions of the piston fit, a beveled surface at the junction of the two portions of the piston, and a beveled seat on the interior of the cylinder on which the beveled surface of the piston acts when it is at the end of its stroke in one direction.

4. A pressure-controlling device comprising

ing a valve chamber and a cylinder, a pack-
ingless piston in said cylinder adapted to
operate on a member which causes the pres-
sure being controlled to build up, said pis-
ton having a beveled surface that rests on
a beveled surface inside of the cylinder,
means for admitting the pressure being con-
trolled to said valve chamber, a port that
establishes communication between said
chamber and cylinder, a diaphragm valve
arranged over said chamber for governing
the flow of the pressure medium through
said port, a raised annular valve seat on the

bottom of said chamber surrounding said
port and normally covering a portion of said 15
valve which is presented to the action of the
pressure medium when the valve is open,
and a spring for seating the valve.

In testimony whereof I hereunto affix my
signature in the presence of two witnesses, 20
this 16th day of November 1912.

GEORGE F. STEEDMAN.
